UNITED STATES PATENT OFFICE.

HENRY ALBERT FLEUSS, OF THATCHAM, AND ROBERT HENRY DAVIS, OF LONDON,
ENGLAND.

BREATHING APPLIANCE.

1,013,541.

Specification of Letters Patent.

Patented Jan. 2, 1912.

Application filed September 29, 1910. Serial No. 584,510.

To all whom it may concern:

Be it known that we, HENRY ALBERT FLEUSS, residing at Dunstan Lodge, Thatcham, Berkshire, England, and ROBERT HENRY DAVIS, residing at 187 Westminster Bridge road, London, England, subjects of the King of Great Britain, have invented new and useful Improvements in or Connected with Breathing Appliances, of which the following is a specification.

Our invention relates to breathing apparatus such as is used by men engaged in rescue work in mines and for like purposes, and comprises a novel construction of the breathing bag forming a part of such appliance.

According to the invention the improved breathing bag, which also forms the caustic soda chamber, is of a rectangular or other convenient shape and is made of strong vulcanized india-rubber, a central longitudinal partition extending from the top of the bag to within a short distance of the bottom thereof, or completely to the bottom thereof and having its lower portion perforated, thus dividing the bag into two compartments. One of the compartments is fitted with an inhaling valve or valve connection and the other with an exhaling valve or valve connection. A third connection is also fitted to the inhaling compartment or to the inhaling connection this third connection being in communication with the oxygen supply, while a fourth connection with a relief valve is fitted at the exhaling end of the compartment. The bottom of the bag contains caustic soda, preferably fused stick, into which the aforementioned central partition dips. With this construction of bag it will be clear that the exhaled breath of the user of the apparatus enters one of the compartments of the bag down which it passes and from which it escapes through the layer of caustic soda before passing to the other compartment of the bag and thence to the inhaling tube.

In breathing bags as used in some types of self-contained breathing apparatus there is a danger that the inner side of the walls, particularly if there be any moisture upon them, may stick together either through an extra deep inhalation by the wearer or, as has sometimes happened, when the bag is pressed upon, the result in such cases being

to prevent the wearer from breathing freely. To obviate this possibility, we fit both sides of the partition of our breathing bag with thin vertical ribs of vulcanized rubber preferably formed integral with the partition, which effectually prevent any sticking of the walls, and always insure a free passage for the inhaled and exhaled air in either of the contingencies described. It often happens, after a mine disaster, that the rescuers are compelled to crawl on hands and knees, or even to lie flat on their stomachs when getting through small apertures such as are frequently met with after a fall of roof. In such cases the bag will inevitably be pressed almost, if not quite, flat, but even then, with our improved bag, there would be a free passage for the air.

To enable the invention to be fully understood we will describe it by reference to the accompanying drawing, in which:

Figure 1 is a sectional side view of a breathing bag made according to the invention. Fig. 2 is a sectional elevation at right angles to Fig. 1. Fig. 3 is a section on the line 3—3, Fig. 1, seen from below. Figs. 4 and 5 are sectional side and end views respectively illustrating a modified form of bag. Fig. 6 is a side elevation of a part of a breathing bag showing the alternate method of connecting the oxygen supply. Figs. 7, 8 and 9 are respectively sectional elevations and plan drawn to a larger scale of a detail hereinafter described, and Fig. 10 is a view of the upper part of the bag illustrating a further modification.

a is the bag proper which, as above stated, is made of vulcanized india-rubber and *b* is the partition which extends from the top of the bag *a* either to within a short distance of the bottom thereof as shown in Figs. 1 and 2 or completely to the bottom thereof, in which case its lower part is formed with the perforations *c*, *c* as shown, in Fig. 4. The partition *b* divides the bag into two compartments *d* and *e*, the compartment *d* being the inhaling compartment and the compartment *e* the exhaling compartment and the said partition is formed with the longitudinal ribs *b'* on either side for the purpose above described.

The inhaling compartment *d* is fitted with a valve connection *f* and with a valve connection *g* in communication with the oxy-

gen supply. The exhaling compartment *e* is fitted with a valve connection *h* and a relief valve *i* as shown in Figs. 1 and 2. This relief valve *i* may be automatic in action or 5 preferably controlled by the wearer of the apparatus, its object being to let off the excess of gas which is purposely delivered to the breathing bag in order to wash out from time to time the nitrogen which is nearly 10 always present in commercial oxygen, as nitrogen is in no way absorbed by the wearer. Also as described above the bottom of the bag is charged with caustic soda. The inhaling and exhaling connections *f* 15 and *h* respectively are in communication by the flexible tubes *j*, *j'* with the mouth piece *k* and a trap *l* is interposed between the latter and the exhaling connection *h* for catching or retaining saliva and any moisture which may be contained in the exhaled 20 breath. For cooling the breath as it passes through the trap we advantageously provide it with a perforated jacket *l'* Figs. 1, 2, 7, 8 and 9 filled with asbestos wool saturated with a mixture of methylated spirit 25 and water in about the proportion of one part of the former to three parts of the latter.

When the appliance is in use the exhaled 30 breath of the person using the apparatus passes through the connection *h* into the compartment *e* down which it passes any saliva or moisture being retained by the trap *l*. On reaching the bottom of the compartment *e* the exhaled breath penetrates 35 through the caustic soda and enters the compartment *d* up which it flows and finally passes out with the oxygen entering by the connection *g* through the pipe *f* to the 40 mouth of the user.

In Fig. 6 we have illustrated the modification wherein the oxygen supply connection *g* is connected to, and opens into the inhaling connection *f*. This construction possesses 45 the advantage that the fresh oxygen does not pass into the bag *a* which becomes warmed in use and consequently raises the temperature of the oxygen when the latter is first introduced into the bag as in the form of our 50 invention shown in Figs. 1 and 2.

Instead of the arrangement of saliva trap *l*, illustrated in Figs. 1 and 2, it may be arranged without the cooling jacket *l'*, as illustrated in Fig. 10, and in addition we may 55 provide a similar trap, but with a cooling jacket interposed between the mouth-piece *k* and the inhaling connection *f*, also, as shown in the said figure. Or both of such traps may be with or without the cooling jacket.

60 It may be added that our object in using a flexible container or breathing bag for the caustic alkali or other solid absorbent of carbonic acid gas is to enable the substance to be shaken up from time to time by the 65 wearer of the apparatus, for the purpose of

removing the carbonated surface, and thus presenting a fresh and active surface for the further absorption of the gas.

Claims:

1. A breathing appliance comprising a 70 bag having a longitudinal partition dividing the bag into two compartments in communication with one another, one of said compartments being provided with a valve and connection through which oxygen is 75 supplied to the user, a cooling trap through which said oxygen passes and a valve and connection through which oxygen is supplied to the apparatus, and the other of said compartments being fitted with a valve and 80 connection for the passage of exhaled air, a moisture trap through which said exhaled air passes and a relief valve provided for the escape of a portion of the exhaled air from the apparatus. 85

2. A breathing appliance comprising a bag having a longitudinal partition perforated at its lower extremity and dividing the bag into two compartments, one of said compartments being fitted with an inhaling valve and connection, an oxygen cooling trap and an oxygen supply connection, and the other of said compartments provided with a connection for the passage of exhaled air, a moisture trap through which the said 95 exhaled air passes and a relief valve provided for the escape of a portion of the exhaled air from the apparatus. 90

3. A breathing appliance comprising a bag having a longitudinal partition provided with ribs on either side thereof and dividing the bag into two compartments in communication with one another, one of said compartments being provided with a valve and a connection through which oxygen is 100 supplied to the user and also a connection through which oxygen is supplied to the apparatus, and the other of said compartments being fitted with a valve and connection for the passage of exhaled air and a relief valve 105 provided for the escape of a portion of the exhaled air from the apparatus. 110

4. In a breathing appliance, the combination with a bag, of a longitudinal partition formed with ribs on either side thereof and 115 dividing the bag into two compartments in communication with one another, of an inhaling valve and connection, and an oxygen supply connection fitted to one of said compartments, and an exhaling valve and connection, a moisture trap and a relief valve fitted to the other of said compartments. 120

5. In a breathing appliance, the combination with a bag, of a longitudinal partition perforated near its lower extremity and dividing the bag into two compartments, said partition being formed with ribs on either side thereof, an inhaling valve and connection, a cooling trap, an oxygen supply connection fitted to one of said compartments, 125 130

and an exhaling valve and connection, a moisture trap and a relief valve fitted to the other of said compartments.

6. A breathing appliance comprising a bag, a longitudinal partition dividing the bag into two compartments, the compartments being in communication through suitable means provided in said partition, one of said compartments being provided with a valve and connection through which oxygen is supplied to the user and also a valve and connection through which oxygen is supplied to the apparatus, and the other of said compartments being fitted with a valve and connection for the passage of exhaled air and a relief valve for the escape of a portion of the exhaled air from the apparatus.
- 10 7. A breathing appliance comprising a bag, a longitudinal partition dividing the

bag into two compartments, the compartments being in communication through perforations at the lower end of said partition, a suitable purifying agent at the point of communication, one of said compartments being provided with a valve and connection through which oxygen is supplied to the user and also a valve and connection through which oxygen is supplied to the apparatus, and the other of said compartments being fitted with a valve and connection for the 20 passage of exhaled air and a relief valve for the escape of a portion of the exhaled air from the apparatus.
